UNITED STATES PATENT OFFICE.

OLIVER COLBORNE, OF CHICAGO, ILLINOIS.

PIE-MACHINE.

No. 927,490.

Specification of Letters Patent.

Patented July 13, 1909.

Application filed May 25, 1908. Serial No. 434,750.

To all whom it may concern:

Be it known that I, OLIVER COLBORNE, a citizen of the United States of America, and a resident of Chicago, county of Cook, State of Illinois, have invented certain new and useful Improvements in Pie-Machines, of which the following is a specification.

The main objects of this invention are to provide an improved form of pie machine which is rapid and efficient in its operation and which is adapted to accomplish the various operations of making pies with a minimum amount of mechanism; to provide an improved form of pie crust trimming mechanism adapted to operate automatically for trimming the crusts on pie tins while such tins are being carried along by a continuously movable conveyer; to provide improved means for moistening the edges of the bottom crusts so as to cause the upper crusts to adhere thereto; and to provide an improved arrangement of the various mechanisms which act upon the pies so that each tin will traverse the circuit twice during each complete cycle of operations, thereby greatly simplifying the mechanism, reducing its cost, and reducing the floor space which it occupies. These objects are accomplished by the device shown in the accompanying drawings, in which—

Figure 1 is a top plan of a pie machine constructed according to this invention. Fig. 2 is a side elevation of the same. Fig. 3 is a front elevation of the same. Fig. 4 is a sectional detail of the dog and trip mechanism which controls the registration of the trimmer with the tins during the trimming operation. Fig. 5 is a detail showing the parts of Fig. 4 in plan. Fig. 6 is a detail showing in front elevation the mechanism which controls the operation of the moistener. Fig. 7 is a top plan of the same. Fig. 8 is an enlarged detail showing the moistening mechanism in side elevation and partly in section. Fig. 9 is a detail showing the arrangement of the stop recesses which coöperate with the spring pressed detent for controlling the position of the moistening brush. Fig. 10 is a detail showing the spring which allows yielding of the trimmer head. Fig. 11 is a detail of the mechanism which causes the movement of the pie tin during the operation of trimming a pie crust thereon, and by means of which the trimmer is caused to operate upon each pie tin but once, while the

pie tin travels twice around the circuit. Fig. 12 is an elevation of the same, some of the parts being shown in section on the line A—A of Fig. 11. Fig. 13 is a section taken on the line B—B of Fig. 12. Fig. 14 is an elevation of the signal mechanism. Fig. 15 is a top plan of the same.

In the construction shown in the drawings, the supporting frame comprises a substantially circular platform or table 1 supported by a central pedestal 2. A conveyer comprising a series of supports 3 for pie tins is arranged to travel around the outer edge of the table 1; and a pie crust forming apparatus 4, a trimmer 5 and a moistener 6 are mounted upon the table so as to overhang the path of the pie tin supports.

Power is applied at the pulley 7 and is transmitted to the crust forming mechanism by means of the shaft 8. The trimmer and moistener are operated by the movement of the conveyer, which in turn is driven from the shaft 8 through the bevel gears 9, the shaft 10, and the mechanism which will be hereinafter described.

The conveyer mechanism comprises a gear 11 loosely journaled on the pedestal 2 concentric with the shaft 10, a plurality of radially disposed arms 12 rigidly connected with the gear 11 and rotatable therewith. Each of the arms 12 has mounted at its end a vertically disposed shaft 13 which carries at its upper end a pie tin support 3, and which is both rotatably and vertically slideable in its bearing on said arm. Each of the shafts 13 has near its lower end a friction pulley 14. Plates 15 are also secured below each of the pie tin supports 3 so as to catch the cuttings of dough which are removed by the trimmer, as will hereinafter appear. Rotation of the gear 11 is accomplished by means of a pinion 16 which is connected with the shaft 10 by mechanism including the bevel gears 17, the friction disk 18 and the friction wheel 19. The friction wheel 18 is normally urged into contact with the friction wheel 19 by the spring 20, and is adapted to be thrown out of such contact by the forked arm 21 which is shifted by a foot treadle 22. The purpose of this treadle mechanism is to permit the conveyer to be stopped while the crust forming mechanism continues to operate, a feature which is of advantage, as it permits the operator to cull out any crusts which are not perfectly formed, and replace such culled

crusts with others, thus insuring that every pie is perfect on being delivered from the machine.

The crust trimmer which is designated 5, as a whole, comprises an arm 23 upon which is rigidly mounted a head 24 carrying a plurality of trimmer rollers 25 which are loosely journaled so as to rotate about vertical axes and have rolling contact with the edges of a pie tin on the adjacent support 3. The rollers 25 are preferably mounted in ball bearings so as to rotate with a minimum of friction, and the studs which carry them are adjustable in the head to suit different sizes of pies. The trimming mechanism also includes means for lifting the shafts 13 so as to carry the pie tins into engagement with the trimming rollers 25, and means for rotating the shaft 13 when its respective pie tin is in contact with the trimming rollers. A spring shown in Fig. 10 insures a uniform pressure between each tin and the trimming rollers, regardless of wear or slight difference in the lengths of the shafts 13. The shafts 13 are lifted by means of a cam track 26 carried by the arm 27, which arm is pivoted at 28 on a bracket 29 of the supporting frame. The arm 27 carries a roller 30 (see Fig. 12) which engages a cam 31 and thereby controls the position of the arm 27 so as to carry the track 26 into or out of position for engaging and lifting the shafts 13 as they traverse said track. The bracket 29 is bent upward and carries a curved friction surface 32, which is normally urged outward by means of springs 33 so as to bear with driving contact against the friction rollers 14 during their passage along that part of their path which is adjacent to the path of the trimmer. The cam 31 is provided in its periphery with a series of alternately high and low seats designated 34 and 35 respectively in Fig. 13 of the drawing. When the roller 30 is seated in one of the low seats 35, as in Fig. 13, the arm 27 occupies the position shown by full lines in Fig. 12, and the shafts 13 will then freely pass above the track 26 without being lifted thereby. When the roller 30 is in engagement with one of the high seats 34, the arm 27 will occupy the position shown by dotted lines in Fig. 12. The rotation of the cam 31 is accomplished by means of a stud or shoulder 36 carried by one of the arms of the gear 11 and so located as to strike the teeth of the star wheel 37 which is rigidly fastened to the cam 31. The crust trimmer arm 23 is loosely journaled concentrically of the shaft 10 and has a limited angular movement so as to permit the trimmer to travel back and forth along the path of the pie tins on the conveyer. A movable detent or draw bolt 38 is carried by the arm 23 and extends downwardly through a slot 39 in the platform 1, being vertically slidable on the arm so as to move into and

out of engagement with a shoulder on each of the arms 12 (see Figs. 4 and 5). A double wedge 40 is located at the end of the slot 39 in position for engaging rollers 41 on the detent 38 and retracting it from engagement 70 with the arm 12 when said arm approaches a position near the end of the slot 39. A spring 42 returns the arm 23 to its normal initial position, said arm being brought to a stop without shock by means of a dash pot 75 43, which may be of any usual construction suitable for the purpose.

The moistening of the edges of the lower crusts of the pies is accomplished by means of the fountain moistener 6 which comprises 80 a pair of brushes extending in diametrically opposite directions from a hollow perforated head 44 (Fig. 8), to which water is supplied from the tank 45, the rate of feed being controlled by the pet-cock 46. The head 44 is 85 rotatable on a horizontal axis so as to turn the brushes of the moistener into and out of position for moistening the pie crusts. Rotation of the head 44 is accomplished by the pinion 47 which meshes with a gear 48 having thereon a series of studs or shoulders 49, which are equally spaced, the angular intervals between them being such that the head 44 will make one quarter turn for each rotation of the gear 48 through such angular interval. The positions of the gear 48 are controlled by a spring detent 48^a which seats in depressions 48^b. One of the arms 12 carries an upwardly extending stud 50 located so as to engage the lowermost stud 49 and rotate 90 the brush head one quarter turn during each passage of said stud 50. Thus, whenever the arm 12 which carries the stud 50 passes the moistener, said moistener will be turned to bring the brush either into or out of position 95 for moistening the pie crust. The stud 50 is so located with respect to its own arm as to turn the brush after its particular pie tin support has passed the brush. The next following pie tin support is preferably marked 100 in a conspicuous manner, as, for instance, by painting the plate which is designated 15^a in Fig. 1 with a distinguishing color.

In order to notify the operator when the conveyer is about to complete a revolution, a 115 signal mechanism illustrated in Figs. 14 and 15 is operated just before the parts arrive at the position in which they are shown in Fig. 1. This alarm mechanism comprises a bell 51 operated by an arm 52 which extends into 120 position for being engaged by the stud 50 and which may, of course, be of any ordinary construction.

The operation of the device shown is as follows:—The conveyer is shown in its normal 125 initial position in Fig. 1. During the normal operation of the machine the conveyer rotates continuously, and the crust forming mechanism is also in continuous operation and is geared so as to deliver pie crusts one at 130

a time at a rate of speed corresponding to the rate at which successive pie tin supports arrive at positions for receiving the crust. Assuming, for example, that a crust is already 5 in position on the delivery platform 53 of the pie crust forming machine, the operator picks up such crust and lays it upon the pie tin which is on the first pie tin support identified 10 in the drawing as 15^a when such support is moving between its position in Fig. 1 and the trimmer, and in this manner the successive crusts are placed upon the successive tins as they traverse this part of their path. If for any reason a crust is found to be faulty, the 15 operator may temporarily stop the conveyer without interfering with the continuous operation of the crust forming device, by disconnecting the friction drive wheels 18 and 19 by means of the pedal 22. Immediately 20 before the first pie tin, with its bottom crust in position, arrives at the crust trimming mechanism, the stud 36 engages the star 37 and rotates the cam 31 so as to lower the track 26. The bottom crusts are therefore 25 carried past the trimmer without contact therewith. The stud 50 now throws the moistener into its operative position immediately before the arrival of the first tin carrying the bottom crust, so that the brush 30 swabs moisture upon the edges of said bottom crust. In this way the whole series of bottom crusts are moistened during the first revolution of the conveyer. As the first pie tin approaches the position in which it is 35 shown in Fig. 1, the alarm 51 is sounded. The operator then feeds to the crust forming device the dough from which top crusts are rolled. It is usual to use different dough for top and bottom crusts. During the 40 continued operation he now places the top crust upon the pies which have been previously filled during their passage between the moistener and the crust rolling device. As the first tin approaches the trimmer during the 45 second revolution of the conveyer, the stud 36 shifts the cam 31, throwing up the track 26. As soon as the pie tin arrives at a position directly below the trimmer 5, its arm 12 is engaged by a detent 38, and the trimmer is 50 carried along with the pie tin in registering position therewith. The track 26 lifts the pie tin into operative engagement with the crust trimming rollers 25, and the roller 14 engaging the friction surface 32 rotates the 55 pie tin so that the rollers 25 will roll around the edges thereof and cut off all of the surplus dough. As soon as the trimming operation is completed, the detent 38 will be withdrawn by means of the wedges 40 and will be incidentally returned to its initial position, ready 60 for trimming the succeeding pie crust. The stud 50 traveling in advance of the first pie tin rotates the moistener head so as to prevent contact of the brush with the finished pie. When all of the pies have been fin-

ished, they are removed from the conveyer during their passage of that part of their path which lies between the moistener and the crust forming device. The alarm is again sounded when the first carrier approaches the 70 position 15^a of Fig. 1, and the whole operation is repeated.

With the construction shown, the conveyer operates continuously, and each pie is completed during two revolutions of the conveyer. 75 This arrangement admits of concentrating the mechanism so as to occupy a minimum amount of floor space, and makes it possible to roll both bottom and top crusts by means of the same crust rolling mechanism, thereby 80 saving the expense of the extra crust rolling mechanism and the additional mechanism which is necessary for operating it.

What I claim as my invention and desire to secure by Letters Patent is:—

1. The combination of a support for a pie tin arranged to travel in a circuit, a crust trimmer and a crust moistener adjacent to the path of said support, and mechanism for automatically causing said trimmer and 90 moistener to operate alternately during respectively different trips of said support around the circuit.

2. The combination of means for carrying a pie tin around a circuit, a trimmer adjacent to the path of such tin, and means controlled automatically to bring the tin into operative engagement with said trimmer during one trip around the circuit and prevent such engagement during another trip. 100

3. The combination of a support for a pie tin arranged to travel in a circuit, a crust trimmer located in position to coöperate with said support for trimming a pie crust thereon, and mechanism adapted to cause 105 said trimmer to operate on said support only during alternate trips thereof around the circuit.

4. The combination of a conveyer adapted to carry a pie tin, a member movable 110 with said conveyer, a trimming roller journaled on said member and adapted to trim a pie crust on such tin through the relative rotation of such tin and roller, and means for causing such relative rotation while the 115 conveyer is in motion.

5. The combination of a conveyer adapted to carry a pie tin, a member arranged to travel along a limited part of the path of said conveyer, a trimming roller journaled 120 on said member and adapted to trim a pie crust on such tin through the relative rotation of such tin and roller, and means for causing such relative rotation while the conveyer is in motion.

6. The combination of a conveyer adapted to carry a pie tin, a member arranged to travel backward and forward along a limited part of the path of said conveyer, a trimming roller journaled on said member and adapt- 130

ed to trim a pie crust on such tin through the relative rotation of such tin and roller, and means for causing such relative rotation while the conveyer is in motion.

- 5 7. The combination of a pie tin support movable in a horizontally disposed path, a trimmer located above the path of said support and adapted to travel along said path, and means arranged to operate automatically for relatively shifting said support and trimmer axially of the pie tin when they are in registering alinement.

8. The combination of a trimmer, a conveyer adapted to carry pie tins in succession 15 to said trimmer, said trimmer being adapted for trimming pies while the conveyer is in motion, and means operating to shift each pie tin in an axial direction relatively to the trimmer while it is in registering alinement 20 therewith.

9. The combination of a conveyer adapted to carry a series of pie tins, the path of said conveyer being of circular curvature at one part, an arm journaled concentrically 25 of said curved part of said path, a trimmer carried by said arm and adapted to engage the edge of a pie tin on said conveyer for trimming a crust thereon, and means for locking said arm to said conveyer when a 30 tin thereon arrives at a position to register with said trimmer and thereby causing the trimmer to travel with said conveyer during the trimming operation.

10. The combination of a conveyer adapted to carry a series of pie tins, the path of said conveyer being of circular curvature at one part, an arm journaled concentrically 35 of said curved part of said path, a trimmer carried by said arm and adapted to engage the edge of a pie tin on said conveyer for trimming a crust thereon, means for locking said arm to said conveyer when a tin thereon arrives at a position to register with said trimmer and thereby causing the trimmer 40 to travel with said conveyer during the trimming operation, and means for automatically disconnecting said arm and conveyer 45 at a predetermined point along said path.

11. The combination of a conveyer having thereon a series of supports adapted to carry pie tins continuously and in succession along a certain path, a crust trimmer mounted to travel forward and back along a limited part of said path, means for insuring 50 the operative registration of the trimmer with the adjacent support during the forward movement of the trimmer, and means for automatically shifting said trimmer backward so as to register with a succeeding 55 support when such succeeding support arrives at a certain predetermined position along said path.

12. The combination of a conveyer having thereon a series of supports adapted to carry 60 pie tins continuously and in succession along

a certain path, a crust trimmer mounted to travel forward and back along a limited part of said path, means adapted to connect said trimmer to said conveyer when a support arrives in position to register with said trimmer, means for disconnecting said trimmer from said conveyer after the trimmer has been carried along a certain distance thereby, and means normally urging said trimmer backward to its initial position. 70

13. The combination of a conveyer, a pie tin support carried thereby and vertically movable thereon, a trimmer located above said support and adapted to travel therewith, a cam surface disposed along the path 80 of said support and movable into and out of position for engaging and shifting said support into engagement with said trimmer, and means adapted to automatically shift said cam surface between said positions at predetermined intervals. 85

14. The combination of means for carrying a pie tin around a circuit, a trimmer adjacent to the path of such tin, a pivoted arm arranged to control the operative engagement of said tin and trimmer, a cam arranged to shift said arm to alternately cause and prevent such engagement, and mechanism adapted to turn said cam at predetermined intervals. 90

15. The combination of means for carrying a pie tin around a circuit, a moistener located adjacent to said circuit and adapted to moisten the edges of a pie crust on a tin during its passage around said circuit, and means 100 controlled automatically to cause the operation of said moistener during one trip of the tin around the circuit, and to prevent such operation during another trip. 95

16. The combination of means for carrying a pie tin around a circuit, a moistening brush mounted adjacent to the path of the tin and movable into and out of position for contact with a pie crust on such tin, means 105 controlled by said carrying means for moving said brush into position for engaging the pie tin during one trip thereof around the circuit and adapted to shift said brush out of such position during another trip. 110

17. The combination of a conveyer adapted to carry pie tins in succession, a head rotatably mounted above said conveyer and having thereon a radially disposed brush movable, through the rotation of said head, into and out of position for engaging the pie 115 tins on said conveyer, said head being hollow and perforated, means for supplying water to the interior of said head, and mechanism adapted to rotate said head to bring the brush into and out of position for engaging the pie tins during respectively different trips of such tins around the path of the conveyer. 120

18. A pie machine, comprising a horizontally disposed table, a conveyer arranged to carry pie tins in succession around the edges 130

of said table, pie crust forming mechanism mounted on said table and adapted to deliver pie crusts adjacent to the path of said conveyer, a crust trimmer and a moistener each located for operative engagement with pie tins on said conveyer and arranged to operate while the conveyer is in motion, and mechanism controlling said trimmer and moistener and adapted to bring the moistener into engagement with each of the tins during one trip of the conveyer and to bring the trimmer into such engagement during a succeeding trip, all being arranged to prevent both trimmer and moistener from operating on the same tin during the same trip.

19. The combination of a pie crust forming device, a crust moistener, a crust trimmer, a conveyer adapted to carry a series of pie tins and arranged to travel in a circuit adja-

cent to said forming device, moistener and trimmer, mechanism controlling the operation of said moistener and trimmer whereby the moistener will be thrown into operation and the trimmer will be thrown out of operation on the approach of a certain tin of the series, and whereby the trimmer will be thrown into operation and the moistener will be thrown out of operation during the next approach of said certain tin, and means for signaling the operator when said certain tin approaches the crust forming device.

Signed at Chicago this 18th day of May, 1908.

OLIVER COLBORNE.
